UNITED STATES PATENT OFFICE.

ARTHUR H. R. BERTHOLD, OF CHICAGO, ILLINOIS, ASSIGNOR TO INTERNATIONAL DENTAL MANUFACTURING COMPANY, OF CHICAGO, ILLINOIS, A CORPORATION OF ILLINOIS.

VALVE FOR DENTAL PLATES.

Application filed November 7, 1921. Serial No. 513,278.

To all whom it may concern:

Be it known that I, ARTHUR H. R. BERTHOLD, a citizen of Germany, having declared his intentions of becoming a citizen of the 5 United States, residing at Chicago, in the county of Cook and State of Illinois, have invented a new and useful Improvement in a Valve for Dental Plates, of which the following is a specification.

10 My present invention relates to dental appliances, and has more particular reference to a valve for controlling a port through the plates or bodies of artificial dentures through which air and saliva may be drawn 15 from back of the plate for the purpose of securing more perfect contact and creating a slight vacuum whereby to seat and retain the plate more securely in the mouth of the wearer.

20 As is well known to the dental profession, as well as to persons using artificial dentures, no little difficulty is experienced in providing a plate that will successfully withstand usage and retain its position in the mouth 25 during certain muscular actions of the tongue or cheeks, or both, such as occur during acts of laughing, coughing, sneezing, or the twisting of the lower jaw. Likewise, it is difficult to retain the plate in position 30 when biting hard or tough substances, such as biting corn off the cob, crusts of bread or eating nuts. These are inherent objections to the artificial dental constructions when 35 made in the ordinary manner, and it is to overcome this defect that I have provided 40 means that will permit the wearer, by a sucking action, to exhaust the air and saliva from back or through the port in the plate, thereby creating a sufficient vacuum to firmly and dependably retain the plate in proper position upon the gums.

I am aware that miniature valves have heretofore been designed to permit of the adaptation of the principle of the vacuum 45 above mentioned, but, so far as I am aware, such valves have almost uniformly depended upon the vacuum back of the plate to retain the valves in closed position, which, as is commonly known, is not dependable as the 50 amount of vacuum that can be employed or produced is not great, and it is my wish to mechanically maintain the valve in closed position by suitable devices so that the slight vacuum which may be created will not alone

be depended upon to retain the valve in 55 closed position. With my present structure, I have provided a valve that is closed and retained in such position by mechanical means as distinguished from those employing only vacuum, and I am thereby enabled to maintain a vacuum between the plate and the mouth tissues and accomplish this without injury to the tissues, and the tending of the air or saliva to leak in behind the plate is materially reduced.

60 I prefer to carry out my invention in substantially the manner hereinafter described, and as more particularly pointed out in the claims, reference being now made to the accompanying drawings that form a part 70 hereof:

In the drawings:

Figure 1 is a plan view of my improved 75 valve applied to dental plate in the preferred manner, the dimensions of the parts being greatly exaggerated.

Figure 2 is an axial section of the structure, the view being taken on line 2—2, Figure 1.

Figure 3 is a plan of the spring or elastic 80 disk for closing the valve, the same being detached from the structure shown in Figure 1.

In the drawings I have employed similar 85 reference characters to designate like parts throughout the views, and for the purpose of clearness the structure has been greatly exaggerated.

As shown, the impression plate 5, which is usually vulcanite, or the like, or of some desired metal, is provided with a shallow 90 suitably shaped depression 6 upon the palatal side thereof and a small aperture 7 is made transversely through the plate at about the center of the depression 6. The casing 95 of the valve structure that fits aperture 7 consists of a hollow shell of any suitable material, the side walls 8 whereof are substantially cylindrical (or any other desired shape) having a laterally projecting peripheral lip or flange 9 extended from the outer edge thereof into the surface of plate 5 upon the lingual side thereof to provide a flush surface around the aperture and to assist in securely retaining the casing in position. It will be understood that other means 100 may be employed for this purpose and still employ the principles herein set forth and come within the scope of my invention.

Extending inwardly from the opposite or inner edge of the cylindrical wall 8 of the casing is a lateral wall 10 that forms the bottom or back of the casing and provides a seat for the valve body, hereinafter mentioned; said bottom or back wall having a centrally disposed aperture 11 and the exterior surface of the back wall surrounding this aperture is countersunk, as at 12, and increased in thickness towards the peripheral portion of the countersink. I prefer to so proportion the structure hereinbefore described that the casing will exactly fit aperture 7 in the denture plate and the depth of the casing will substantially correspond with the thickness of plate 5 at the location of the aperture.

The valve comprises a thin disk 13 preferably corresponding in outline with the interior of the casing in which it is positioned, and centrally therefrom extends the stem 14 that projects through aperture 11 and the outer portion whereof is provided with an enlargement or head 15 substantially as shown in Fig. 2 of the drawings. As seen, the stem 14 at or adjacent the junction with head 15 is reduced slightly, providing an annular groove 16 thereabout. In order to mechanically seat the valve, I have provided a flexible disk 18 of preferably segmental shape, that is, a V-shaped recess or slot 19 is formed therein with the vortex of the V positioned at the axis or center of the disk, and preferably terminates in a centrally disposed enlargement or aperture 20 of sufficient size to fit around the grooved portion 16 of the valve stem, as seen. This disk I prefer to make of flat celluloid so that after the valve has been opened, as illustrated in Fig. 2 (in which the disk is caved into the countersink 12) the flexibility of the disk will pull stem 14 through aperture 11 of the casing and seat the valve. While celluloid has been found very effective in fabricating disk 18, other materials may be employed that are found to be suitable for the purpose, and if desired the enlargement 20 may have a lateral slot 21 to further assist in assembling the disk with stem 14.

For the purpose of insuring the maintaining of the vacuum back of the denture plate 5 and to prevent leakage around the disk and casing I prefer to interpose a washer or packing 22 between the valve disk 13 and seat 10 in the back portion of the casing, and this washer 22 may be made of soft rubber, or other suitable material as desired, being provided with a central hole 23 through which stem 14 may pass.

When installed in a denture plate the lingual side of the latter presents a smooth surface to the patient's tongue, and, owing to the provision of the depressed area 6 in plate 5 no portions of the valve structure

will project above the palatal side of the plate to touch the roof of the user's mouth, or to irritate the tissues thereof.

It is believed the use of the structure will be obvious from the foregoing description, therefore it is sufficient to state that, after an artificial denture has been positioned upon the gums or roof of the mouth, a slight sucking action by the tongue unseats the valve by pulling the valve disk 13 outwardly against the yielding action of the flexible disk 18 which permits the air and saliva that may remain back of the plate to be exhausted through the V-shaped slot or recess 19, the casing aperture 11 and between the casing, washer and valve disk, thus creating a vacuum between the denture plate and the gums or roof of the mouth.

The principles of my valve may be used in conjunction with denture for the lower jaw, and I desire it understood that refinements and modifications of my invention are fully contemplated as coming within the scope of the appended claims. Likewise, it will also be apparent that casing 8—10, herein described, for carrying and seating valve disk 13 and other associated parts may be dispensed with, and in lieu thereof denture plate 5 may be provided with a suitable aperture and the contiguous portion of the plate shaped to substantially conform with the shaped portions of the casing so that the valve-disk, the flexible disk and other associated parts may be co-operatively assembled with each other and with the denture plate. This could be readily accomplished by providing a matrix of the desired shape and molding the valve seat the countersink, etc., at the same time the denture plate is fabricated.

What I claim new is:

1. A suction valve for denture plates comprising a casing of relative small sectional dimension and provided with an aperture, a disk in said casing adapted to close said aperture, a stem extending from said disk through said aperture, and a disk-shaped spring upon the exterior of said casing and co-acting with the stem, whereby to maintain said disk in a normal position to close said aperture.

2. A suction valve for denture plates comprising a casing of relative small sectional dimension and provided with an aperture, a disk in said casing adapted to close said aperture, a stem extending from said disk through said aperture, and a spring plate of normally concave section upon the exterior of said casing and coacting with said stem whereby to maintain said disk in a normal position to close said aperture.

3. A suction valve for denture plates comprising a casing of relative small sectional dimension and provided with a central aperture, a disk in said casing adapted to close

said aperture, a stem extending from said disk through said aperture, and a disk-shaped spring upon the exterior of said casing and co-acting with the stem to maintain 5 said disk in a normal position to close said aperture, said casing provided with a concave seat on its exterior in which said spring

is positioned whereby to limit the pull of the stem upon said spring when the disk is unseated.

Signed at Chicago, county of Cook and State of Illinois, this 15th day of October, 1921.

ARTHUR H. R. BERTHOLD.
